Primary Examiner—Nelson C. Holtje**Assistant Examiner—M. N. Pandozzi****Attorney, Agent, or Firm—Ryan, Kees & Hohenfeldt****[57] CLAIM**

The ornamental design for a luminescent tap handle, as shown and described.

DESCRIPTION

FIG. 1 is a top, front perspective view of a luminescent tap handle showing my new design;

FIG. 2 is a front elevational view, the rear elevational view being a mirror image thereof;

FIG. 3 is a side elevational view thereof;

FIG. 4 is a top plan view thereof; and,

FIG. 5 is a bottom plan view thereof.

FIG. 1
